DESIGN FOR A VEGETABLE-DISH.

Design No. 12,509, dated October 4, 1881.

UNITED STATES PATENT OFFICE.

ELIJAH MOUNTFORD, OF TRENTON, NEW JERSEY.

DESIGN FOR A VEGETABLE-DISH.

SPECIFICATION forming part of Design No. 12,509, dated October 4, 1881.

Application filed July 30, 1881. Term of patent 3½ years.

To all whom it may concern:

Be it known that I, ELIJAH MOUNTFORD, a citizen of the United States, residing at Trenton, in the county of Mercer and State of New Jersey, have invented and produced a new and original Design for Vegetable-Dishes, of which the following is a specification, reference being had to the accompanying photographs, which form a part of this specification.

10 The figure represents a view of my newly designed dish, showing the pillars lettered A, the handles lettered B, the knob on dish-cover lettered C, and the feet lettered D, the decorated edges of the dish lettered E, and the lines 15 on dish-cover lettered F F.

I claim—

The design for a vegetable-dish herein shown and described, the same consisting of a dish of an oblong shape, ornamented at the corners of the same by pillars A A, and the feet D D, the 20 handles B B, and the knob on dish-cover C, the decorated edges of the dish E, and the lines on dish-cover lettered F F F.

In testimony whereof I affix my signature in the presence of two witnesses.

ELIJAH MOUNTFORD.

In presence of—

G. D. W. VROOM,
ANDREW JAS. SMITH.
